UNITED STATES PATENT OFFICE.

JOSEPH A. SHAW, OF RIMERSBURG, PENNSYLVANIA.

RAILWAY-SIGNAL.

1,043,471.

Specification of Letters Patent.

Patented Nov. 5, 1912.

Application filed February 11, 1911. Serial No. 608,023.

To all whom it may concern:

Be it known that I, JOSEPH A. SHAW, a citizen of the United States, residing at Rimersburg, in the county of Clarion and State of Pennsylvania, have invented certain new and useful Improvements in Railway-Signals, of which the following is a specification, reference being had to the accompanying drawings.

10 This invention relates to improvements in railway train signaling devices and especially with reference to improvements in the valves of the compressed air operated signaling apparatus by means of which the conductor of a train can signal the engineer, the object of the invention being to combine with the lever of the valve means operated thereby, for closing an electric circuit including an electric signaling lamp or other translating 15 device, whereby when the conductor pulls the signal cord in a coach to open a discharge or release valve in one end of the coach in order to signal the engineer, the lamps will be caused to flash and thereby 20 assure him that the valve has operated.

25 The invention consists in the construction, combination and arrangement of devices hereinafter described and claimed.

In the accompanying drawings—Figure 1 30 is a vertical sectional view of a train signaling valve operated with my improved circuit closing device. Fig. 2 is a detail sectional view of the same on the plane indicated by the line *a—a* of Fig. 1.

35 The signal valve 1 is of the usual construction. The body of the valve is indicated at 2, and has a chamber 3, a by-pass 4, a connection 5 to the signal whistle, a valve seat 6 at the inner end of the connection 5, 40 and to which the duct or by-pass 4 leads, an opening 7 in the bottom of the body 2, and which communicates with the by-pass 4, and a bushing 8 in the said opening 7, said bushing having a head 9, which bears on the 45 boss or portion 10 of the valve casing, through which the said opening 7 extends.

The cover 11 of the body 1 is provided 50 with a connection 12 for the signal line or train pipe. A diaphragm 13 is secured between the body of the valve casing and the cover 11, the cover having a chamber 14, above the diaphragm which chamber communicates with the signal line at 15, and also 55 communicates with the by-pass 4, at 16. The

valve 17 closes on the seat 6 and has a stem 55 18 which extends through and operates in the bushing 8. The upper portion of the valve stem is cylindrical in form and fits closely in the bushing. Its lower portion is provided with channels 19 and there is also 60 a circumferential channel 20 in the valve stem which is normally below the upper end of the bushing as when the valve is in its closed position on the valve seat 6. The valve stem has a head 21 which bears against 65 the under side of the diaphragm 13 and also has a threaded projection 22 which extends through a central opening in the diaphragm, a washer or disk 23 being secured on the upper side of the diaphragm by a nut 24 70 which is screwed on the threaded stud 22 so that the diaphragm is clamped between the head 21 and the disk 23 and hence the valve stem is attached to the diaphragm. The valve stem has an upwardly extending 75 arm 25 which operates in a stuffing box 26 with which the cover is provided.

A bracket 27 is secured on the cover by a bolt 28 and has a vertical arm 29 provided at its upper end with a threaded stem 30. 80 A clevis 31 is secured to the said stem, and hence is vertically adjustable and is provided at its upper end with a pair of ears or lugs 32 between which is disposed the inner end of the valve lever 33, said valve 85 lever being fulcrumed on a bolt 34 which passes through the said lugs or ears. A clevis 35 which is similar to the clevis 31 is screwed on the threaded stem of the valve arm 25 and hence is adjustable thereon, and 90 is pivotally connected to the valve lever as at 36. Jam nuts 37, 38 are respectively located on the threaded stems of the arms 29, 25, and coact with the clevises to secure the latter at any desired vertical adjustment. 95

A bracket 39 is secured on the cover by a bolt 40, and is provided at its outer end with a fork 41, the sides 42 of which are provided with oppositely disposed horizontal arms 43 which extend toward each other, and 100 form the core or pole pieces of electro-magnets, the windings 44 of the electro-magnets being included in open circuit with the electric signaling lamps or other translating devices at the ends of the car and also in the 105 engineer's cab. Contact strips 45 are insulated from the pole or core pieces of the electro-magnets by insulators 46 each of

which has an arm 47 that bears against the under side of one of the core pieces and a vertical arm 48 which bears against the end thereof. The said contact strips are secured 5 to the insulators by screws 48^a which also connect said contact strips electrically with the windings of the electro-magnet, and the said contact strips and the insulators are secured to the core pieces by screws 49. The 10 lever 33 operates in the space between the core pieces of the electro-magnet and is provided with a contact strip 50 which is secured thereto, and insulated therefrom, the insulator being shown at 51. The said contact strip 50 is normally below the opposed 15 horizontal arms 52 of the contact strips 45.

The operation of the invention is as follows: Normally the pressure of the air is equal in the chamber 3 below the diaphragm 13, and in the chamber 14 above said diaphragm. When the conductor wishes to signal the engineer, he pulls the usual signal cord and hence opens the usual releasing valve which allows air to escape from the 20 signal line and hence the pressure in the chamber 14 is reduced. Hence owing to the greater pressure in the chamber 3, the diaphragm 13 is moved upwardly, thereby opening the valve 17 from the seat 6, and 25 permitting air from the signal line to pass through the duct 4 or by-pass and through the connection 5 to the signal whistle so as to blow the whistle, and the whistle continues to blow until the leakage of air from 30 the chamber 3 through the bushing 9 and the channels in the valve stem brings about an equalization of pressure in the chambers 3 and 14 and hence causes the diaphragm to reclose the valve 17 against the seat 6. 35 When the valve is moved upwardly by the diaphragm as above stated, owing to the connection between the valve and the lever 33 said lever is moved upwardly at its free 40 end and causes its contact strip 50 to engage 45 the arms 52 of the contact strips 45 and thereby close the electric circuit which includes the signal lamps in the ends of the coach and the signal lamp in the engineer's cab thereby causing the said lamps to flash 50 thus indicating both to the engineer and to the conductor that the signal devices have been operated. Should the signal whistle fail to blow the engineer will realize that the pipe leading from the signal valve to 55 the signal whistle has become clogged or else that the signaling apparatus is otherwise out of order, and will take steps accordingly.

Should the conductor when he pulls the signal cord, fail to see the lamps flash at the 60 ends of the coach, he will be apprised by that fact that there is something wrong with the signal system.

It sometimes happens owing to the noise of the train and atmospheric conditions, 65 that the conductor fails to hear the engineer

answer his signal with the locomotive whistle when he pulls the signal cord. My improved devices which cause electric lamps or other signaling devices to be operated, by the signal valve, enable the conductor to know positively that the signal system is in working order. 70

By the provision of the electro-magnets on the arms of the brackets 39, the circuit closing elements 50, 52 are included in a magnetic field, which has the effect, when the circuit is broken, of subduing the electric arc in the gap between said circuit closing elements and preventing the said arc from burning away said elements as rapidly as would otherwise be the case. 80

I claim:—

1. A device of the character described, including a lever, means for moving said lever, an angular arm, a support to which one end of said arm is secured, the other end of said arm being projected upwardly and formed with a fork, the upper extremities of the members of the fork being turned inwardly toward each other and spaced one 90 from the other, electro-magnets mounted on said inturned extremities and of which said extremities constitute the pole pieces, angular contact strips connected to said electro-magnets and insulated from the pole pieces 95 thereof, a contact member carried by the said lever at one end of the latter and normally lying below the upper extremities of the first named contact pieces, whereby an upward movement of said end of the lever 100 will effect the contact of the first named contact pieces with the contact carried by the lever, and a normally open circuit in which said electro-magnets are included.

2. In a device of the character described, 105 the combination of a lever, a support therefor, means for raising and lowering said lever, an angular arm, a support to which one end of said arm is secured, the other end of said arm being extended upwardly 110 and formed with a fork, the upper extremities of the members of the fork being turned inwardly toward the other, electro-magnets mounted on said extremities and of which said extremities constitute pole pieces, angular contact pieces secured to the electro-magnets and insulated from the pole pieces 115 thereof and formed with upper inwardly turned extremities, a transversely extending contact piece carried by the free end of said 120 lever and adapted to be moved upwardly thereby into contact with the inwardly turned extremities of the first named contact pieces, and a normally open circuit in which said electro-magnets are included. 125

3. In a device of the character described, a lever, a support therefor, means for moving said lever, an angular arm, a support to which one end of said arm is connected, the other end of said arm projecting up- 130

wardly and being formed with a fork, contact pieces formed with extremities turned toward each other and arranged in laterally spaced relation and carried by the respective members of the fork, and a contact piece carried by the free end of said lever and insulated therefrom and adapted to be raised by said lever into engagement with

the inwardly turned extremities of the first named contact pieces. 10

In testimony whereof I hereunto affix my signature in the presence of two witnesses.

JOSEPH A. SHAW.
